MECHANISM FOR SYNCHRONIZING
TANDEM MACHINES

William Pechy, Elizabeth, N. J., assignor to
American Can Company, New York, N. Y., a
corporation of New Jersey

Application September 4, 1935, Serial No. 39,181

11 Claims. (Cl. 198—102)

The present invention relates to machines which perform work cooperatively and successively in tandem upon sheets of tinplate or the like, and has particular reference to the automatic synchronizing of these machines so that the sheets may be transferred from one machine to another and work performed upon them in an uninterrupted flow.

An object of the invention is the provision of an apparatus for automatically synchronizing the cooperative action of the feeding mechanism of one machine with the feeding mechanism of another so that there is at all times a receiving unit of the latter in timed receiving position relative to a discharge unit of the former mechanism.

Another object of the invention is to provide, in such tandem machines, an automatic drive, such as an overrunning clutch, which permits the operation of one of the machines independently of the other.

A further object of the invention is to provide such synchronized machines with detecting means which is sensitive to and is actuated by small but important mechanical or physical changes, such as wear and temperature, in the various parts of the machines to thereby control the synchronizing of the mechanism affected by such changes.

A further object of the invention is to provide the said synchronizing mechanism with starting and stopping devices actuated by the detecting means.

Numerous other objects and advantages of the invention will be apparent as it is better understood from the following description, which, taken in connection with the accompanying drawings, discloses a preferred embodiment thereof.

Referring to the drawings:

Figure 1 is a plan view of a pair of machines with drives and synchronizing mechanism embodying the present invention;

Fig. 2 is a larger scale sectional side view of parts of the machines and synchronizing mechanism, the latter being shown in section as indicated by the line 2—2 in Fig. 1;

Figs. 3 and 4 are sectional views taken at 3—3 and 4—4, respectively, in Fig. 2 to show details of assembly of detector and holding-on cams and switches;

Fig. 5 is a sectional elevation taken at 5—5 in Fig. 2 to show construction of the mechanical drive cut-out;

Fig. 6 is a sectional elevation taken at 6—6

in Fig. 2 showing "retard" and "advance" cams associated with the drive mechanism;

Fig. 7 is a sectional elevation taken at 7—7 in Fig. 2 showing a reduction gear drive of the synchronizing mechanism; and

Fig. 8 is a wiring diagram illustrating the electrical hook-up of the various elements embodied in the present disclosure.

To illustrate the operations of a preferred embodiment of the instant invention, a coating machine indicated generally by the letter A is shown in Fig. 1, which applies a film of lacquer L or the like substance to metallic sheets fed therethrough. The coated sheets coming from this coating machine are transferred to an endless carrier rack of a drying oven B of well known construction wherein the drying of the lacquer is accomplished. A clutch device C and a synchronizing mechanism D, shown intermediate and sidewise of the machines A and B, provide a flexible, synchronizing and automatically adjustable connection between the tandem machines.

The operation of these various units will now be described in detail in a sequence of presentation which will first develop the cooperation of the essential elements of machines A and B, and then proceed to a fuller consideration of the mechanical operation of clutch device C and synchronizing mechanism D in their relations to machines A and B. This will be followed by a more detailed description of the electrical and mechanical devices included in the mechanisms C and D by reference to the diagram in Fig. 8.

Referring to Fig. 1, the coating machine A, including a pair of feed chains 21 for propelling the sheets S through the coating rolls, and a pair of cooperating delivery chains 22 for advancing the coated sheets into the reach of the oven carrier, is driven by a motor or prime mover 23 through a motor pulley 24, through a belt 25 and the machine drive pulley 26.

The pulley 26 is mounted upon a feed shaft 29, which drives sprockets (not shown) over which the chains 21 are driven, and also drives sprockets (not shown) over which the chains 22 are driven the latter also taking over idler sprockets 31 (Fig. 2) mounted on shaft 32, which is journaled in the discharge end of a delivery table 33.

The chains 21 receive uncoated sheets S and feed them to a coating roll 35 which applies a film of lacquer or like coating material to the surface of the sheet, the coated areas being indicated by stippling.

The coated sheets are then engaged by lugs or feed dogs 36 on the delivery chains 22 and are advanced to the delivery end of the machine A, where they are received or picked up by substantially U-shaped prongs or flights 41 of oven conveyor chains 42.

The chains 42 are driven either from the motor 23 or from an oven motor 43 in a manner which will be described later. The oven motor 43 may be termed an auxiliary motor or mover. Either motor drive revolves an oven drive sprocket 44, mounted on an oven drive shaft 45 having bearings in brackets 46 secured to a frame 47 of the oven B, a collar 48 pinned to shaft 45, adjacent a bearing 46, preventing endwise movement of the shaft. Conveyor chain sprockets 51 are keyed to the shaft 45 intermediate of the bearings 46, where they engage and drive the conveyor chains 42. Conveyor chain sprockets 52 support the conveyor chains adjacent the receiving section of the conveyor and are mounted on a shaft 53 journaled in bearings 54 and 55 on the oven frame 47. Collars 56 pinned to shaft 53 adjacent bearings 54 and 55 prevent endwise movement of the shaft.

The sheet holding prongs or flights 41 are of substantially U-shaped or looped construction, one of the ends of the loop being fixed in one of the chains 42 while the other end is secured to the other of the chains 42. The prongs 41 are equally spaced from each other and this construction gives a series of substantially parallel sheet supports which are moved through the oven B at a speed consistent with the adequate drying of the coated surfaces of the sheets. Such an oven, being comparatively long, comprises a great many moving parts, which are subjected to high and changing temperatures producing expansion and contraction of the metal parts and resulting in mechanical maladjustment, in addition to such usual maladjustments as are caused by wear in sprockets and chain links, twists in shafts, etc.

Any or all of these maladjustments usually occur while the machines are in operation. A disturbance of timed relations then results between the receiving prongs 41 of the oven B, and the delivery lugs 36 of the coating machine A. A sufficient disturbance in timing at these and other points may result in damage to machine elements and articles or sheets operated upon. It is obvious that automatic synchronizing of the receiving prongs 41 with the delivery lugs 36 is highly desirable for the efficient and uninterrupted operation of this tandem hook-up and this the instant invention affords. An exemplary embodiment of such an automatic synchronizing mechanism and clutch device will now be described.

Referring again to Fig. 1, it will be seen that a sprocket 61 is mounted on feed shaft 29, which drives a sprocket 62 through a chain 63 which takes over both sprockets. Sprocket 62 is fixed to a shaft 64 journaled in a bearing 65 formed in a base 66 mounted on a sub-base 67. A bevel gear 68 is pinned to the outer end of the shaft 64 and meshes with a bevel gear 69, keyed to a shaft 71 of the clutch device C (see also Fig. 2).

The oven motor 43 is also connected to the drive clutch device C, a coupling 75 connecting a motor shaft 76 to a worm shaft 77 (see also Figs. 2 and 5). This drive is used on occasions when it is desired to keep the oven B in operation while the coating machine A and motor 23 are shut down. Such occasion arises, for instance, when it is desired to make changes on

the coating machine A, at which time the coating machine would be stopped and the already coated sheets S would be maintained in motion through the oven B.

The automatic switching from a common drive for both machines, effected by motor 23, to an independent oven drive by motor 43, will now be considered.

The shaft 71 is formed integrally with a plate or pawl arm 81 (Fig. 2) and is journaled in an upper half-bearing 82 formed in a cover 83 (see also Fig. 5), bearing 82 being bolted to a lower half-bearing 84 formed in a clutch housing 85, which is integral with the base 66.

A pawl 88 is pivotally mounted on the pawl arm 81 by a shouldered pivot screw 89, and its free extremity is held, under spring pressure, against the periphery of a single tooth barrel ratchet 91 by a spring 92 set in recesses 93 and 94 formed respectively in the pawl 88 and an outwardly extending pawl arm flange 95. As shown in Fig. 5, the pawl 88 is in driving position, engaging a tooth 96 of the barrel ratchet 91, through which it drives a shaft 97, keyed to the ratchet 91. Shaft 97 is journaled at the left extremity (Fig. 2) in a bore 98 of the shaft 71, and adjacent the right end of the ratchet, the shaft 97 is journaled in a pair of half bearings. The upper half-bearing 101 is formed in the housing cover 83 and the lower half-bearing 102 in the housing 85.

When the common drive, or coating machine motor 23 is stopped, and the independent or oven motor 43 is started, the pawl 88 no longer impels the ratchet 91, but remains idle. Worm shaft 71, however, is rotated and, between housing bearings 103 and 104 (see Fig. 5) in which it is journaled, a worm 105 (see also Fig. 2) is fixed to the shaft and meshes with a worm wheel 106. The worm wheel is freely mounted on an extension 107 of the ratchet 91, and carries a pawl 111 pivotally mounted on a shouldered pivot screw 112 secured in an extension 113 of the worm wheel. The pawl 111 like pawl 88 is held against the ratchet 91, in this instance, by a spring 114 (Fig. 5) and engages the tooth 96 to drive shaft 97 while pawl 88 remains idle.

In this pair of machines being considered, the moving parts in the coating machine A are few compared with those in the oven B. Therefore the possibilities for maladjustment in the coating machine parts which would affect the timing between the lugs 36 and prongs 41 are negligible whereas the great number of parts in the oven conveyor as well as the temperature variations affecting those parts give rise to timing maladjustments of frequent and varying degrees. The shaft 97 is the driving shaft for the oven whether the motor 23 or the motor 43 is operating. It is desirable therefore to attach a synchronizing controlling mechanism to moving parts beginning with shaft 97 and those beyond this point. Description of such controlling mechanism, other than that used in driving will be reserved until later when the combined electrical and mechanical synchronizing mechanisms will be described in detail.

The right end (Fig. 2) of shaft 97 is journaled in a trunnion 121 of a speed change housing 122. This trunnion is, in turn, mounted in a bearing 123 of a bearing bracket 124. This bracket is bolted to the sub-base 67. Another bracket 125, also bolted to the sub-base 67, is provided with a bearing 126, in which is journaled a trunnion 127 formed in a housing cover 128, bolted to

the housing 122. The housing 122 and its cover 128 may thus be rotated in bearings 123, 126.

On the right extremity of shaft 97 (Fig. 2) a gear 131 is cut integral with the shaft. This gear 5 meshes with a smaller intermediate gear 132, formed integrally with a shaft 133, on which is formed another larger intermediate gear 134. The shaft is journaled at one end in a bearing 135 formed in the housing 122, and at the other 10 end in a bearing 136 formed in the cover 128. Gear 134 meshes with a small driven gear 141, formed integrally with a stub shaft 142 which is journaled in the trunnion 127 and coupled to a long oven drive shaft 143 through a coupling 144.

15 Shaft 143 is an extremely long one, so that a purpose of the gears 131, 132, 134, 141 is to considerably increase the speed of the driven shaft 143 relative to the driving shaft 97, and thereby reduce the torque in the long shaft 143 (see Fig. 1), which extends nearly the full length of the oven B to the place where it is journaled in a bearing 145 of a base 146.

20 A bevel gear 151 is keyed to the remote end of shaft 143, and meshes with a larger bevel gear 152, which is keyed to a short shaft 153. Shaft 153 is journaled in a bearing 154 formed in the base 146 and carries at its inner extremity a sprocket 155 which is keyed to the shaft. The larger sprocket 44 is driven from sprocket 155 25 through a chain 156 which takes over both sprockets. The speed of shaft 45 is decreased considerably from that of shaft 143 by the gearing relationship of bevel gears 151, 152 and the sprockets 155, 44. The oven drive from this point 30 on to the shaft 153 has already been described.

35 Synchronism between the initial drive elements of the coating machine A and shaft 97 has been shown to be effected through the mechanism of clutch device C, pawl 88 engaging the ratchet tooth 96 to establish timed relations between shafts 71 and 97, whenever the common drive motor 23 is operating. Synchronism between shaft 97 and the terminal element shaft 53, however, and between the prongs 41 and the lugs 36, 40 requires more delicate automatic adjustment. This is due, in part, to the already mentioned physical and mechanical variables caused by the long oven and the high temperatures maintained 45 therein. This latter synchronism involves the use of electro-mechanical devices which will now be described.

50 Referring to Fig. 2, a hub 161 is pinned to the shaft 97. An "advance" cam 162, and a "reverse" cam 163 are formed integrally with the hub 161. These cams operate respectively an advance 55 switch 164 and a reverse switch 165. Other synchronizing cams and switches are indirectly connected with the oven sprocket shaft 53 (see top of Fig. 2). They are "holding-on" cam 171 and 60 "detector" cam 172 which operate "holding-on" switch 173 and "detector" switch 174, respectively. The four cams and switches just mentioned cooperate in a manner to be described later.

65 Switches 164 and 165 are fastened to the inner side of a cylindrical housing 175 (see Figs. 2 and 6), and a flange 176 of the housing is seated in a recess 177 formed in bearing bracket 124, where the flange is secured by clamps 178 and bolts 179. When the machines are set up, initial 70 setting of the switches 164, 165 with respect to their cams 162, 163 is effected by loosening bolts 179 and rotating the cylindrical housing 175 to the desired position, and then reclamping it in that position.

75 The synchronizing mechanism immediately as-

sociated with shaft 53 is driven by a large gear 181 (see Figs. 1, 2, 3, 4) keyed to the shaft 53 (Fig. 4). This gear meshes with a smaller gear 182 formed at one end of a shaft 183, which is journaled in a bearing 184 formed in a plate 185. The plate is pivoted on the reduced extremity of shaft 53 (Fig. 4) and clamped at its ends (see Figs. 1, 2) by clamps 186 and bolts 187 to a bracket 188 which in turn is bolted to the bearing 55. Adjustment of cams 171, 172 relative to 10 their switches 173, 174 is effected by loosening bolts 187, turning plate 185 about its pivot shaft 53 to the desired position, and retightening the bolts.

15 Shaft 183 carries holding-on cam 171 and detector cam 172 which are keyed to the shaft. The gear ratio of gears 181, 182 is such that shaft 183 makes one revolution for every two chain prongs 41 which pass over the driven sprockets 52. Holding-on cam 171 has two rises and detector cam 172 has two drops in every 360 degrees of rotation so that switches 173, 174 which are mounted on plate 185 are actuated once every 180 degrees of cam rotation, or once for each prong 41 which passes over the sprockets 52.

20 Shaft 97 makes one complete revolution for every prong 41 which passes over the sprockets 52, therefore advance cam 162 and reverse cam 163 have but one rise in 360 degrees of rotation. All of these cams (171, 172, 162, 163) actuate 25 their respective switches once during a predetermined period which, in this case, is limited to the lapse of time between the passage of one prong 41 and another over the driven oven sprockets 52.

30 When such conditions exist as to warrant an advance in the position of shaft 53 with respect to shaft 97 the switches just mentioned are actuated in a manner to be later described to start a reversible synchronizing motor 191 (see Fig. 1) 35 which then rotates its shaft 192 in an "advance" direction. A motor sprocket 193 is keyed to the shaft 192 and a chain 194 takes over it and also over a larger sprocket 195 pinned to a worm shaft 196 (see Figs. 1, 2, 7) journaled in bearings 40 197, 198 of the bracket 125.

45 A worm 201 is keyed to the shaft 196 intermediate the bearings 197, 198 and meshes with a worm wheel 202 keyed to a reduced extension 203 of the trunnion 127. Rotation of the worm wheel 202 by the motor 191 thus imparts rotation to the cover 128 and housing 122. Such rotation also rotates the axis of shaft 133 about the axis common to shafts 97 and 143 and in this instance, causes an increase in the rotation of shaft 143 50 with respect to shaft 97.

55 This increase in rotation may also be considered as an increase in the gearing ratio between shafts 97 and 143 as long as motor 191 is operating in an "advance" direction. This increase in rotation is transmitted through the mechanism already described to shaft 53 to reestablish normal relations with shaft 97. Reversing of the motor when conditions warrant a retarding of shaft 53 60 with respect to shaft 97 likewise effects a slowing down of shaft 53 with respect to shaft 97 to reestablish normal conditions.

65 The wiring diagram of Fig. 8 will now be considered in more detail.

70 Electrical energy is supplied to the various units in any suitable manner, as by two generators. A direct current generator 205 is indicated in the upper right corner of Fig. 8 as a source of electrical energy for the detecting circuits associated with the various control and synchronizing 75

switches, relays, etc. At the bottom of the diagram, an alternating current generator 206 is symbolized as the source of power for the three motors (23, 43, 191) and some relays.

5 A three-pole double throw switch 207 on the lower right side permits switching from the one to the other of motors 23, or 43. The switch is shown open, but when swung over to the right, current flows through generator supply wires 211, 10 212, 213 to switch connecting wires 214, 215, 216, thence through the switch 207 to wires 217, 218, 219 which lead the current to the oven motor 43.

15 For the sake of brevity in describing the path of this and other alternating current circuits reference is merely made to the current leading or flowing to the energized elements.

If the switch 207 is thrown to the left, the current flows through switch 207 to wires 221, 222, 223 and thence to the coater motor 23. This connection sets up the operation of both coating machine A and oven B as previously described.

20 With the two machines thus in operation, and the cams and switches previously referred to in properly adjusted or set condition, the operation 25 of the synchronizing mechanism is as follows:

In normal operation, no synchronizing action 30 is necessary. At such time, current does not flow through any of the detecting circuits as one or more of the switches 164, 165, 173, 174 are open. 35 The cams and switches are in "normal" operating positions in the diagram and taken at a detecting interval.

When the oven prongs 41 lag behind a proper 40 timed relation with the coater delivery lugs 36, due to the physical or mechanical causes previously mentioned, it is essential to advance prongs 41 with respect to lugs 36. This advance is effected by energizing the synchronizing motor 191 so that it rotates in the direction which will 45 be referred to as an "advance" direction, and means that it imparts to the long drive shaft 143 a slightly increased speed of rotation which ultimately advances the prongs 41 with respect to lugs 36.

45 The means for effecting this "advance" will now be explained. Cams 162 and 163 (Figs. 2 and 8) rotate in clockwise direction at constant speed, being directly connected to the shaft 91. Cams 171 and 172 lag behind the normal timed relation with cams 162, 163 when the prongs 41 lag behind. Cam 171 engages and opens switch 173 for a short interval once for every prong 41 which passes over shaft 53. Cam 172 engages and opens switch 174 for nearly all of the time switch 173 is closed. When these cams lag behind it is equivalent to saying that the cams 162 and 163 are advanced relative to them, and for convenience it may be assumed that in this instance cam 162 is rotated clockwise until switch 164 is closed. Cam 60 163 is also rotated through the same arc, but switch 165 will still be open. At this instant current from generator 205 flows through wires 224, 225 to switch 174 where it is connected through contact 226 to wires 221, 228 which lead to "advance" switch 164 which is now closed.

The current continues through contact 229 and wires 230, 231, 232 to a single contact relay 233 which is energized, wires 234, 235, 236 completing the circuit back to generator 205.

70 When relay 233 is thus energized, its contacts at 237 are opened but current from wire 231 passes through wire 238 to the contact 239 of normally closed relay 240, the wires 241, 242 which conduct the current to a double-contact "advance" relay 245, which is then energized, the

wires 246, 247 and 236 completing the circuit back to generator 205. The purpose in opening relay 233 will be explained later.

The energized relay 245 closes its contacts 251 and 252. Closing of contact 251 shorts the circuit which includes detector switch 174 and "advance" switch 164. Contacts 251 and 252 are held closed by current which passes through switch 174 until the high spot on holding-on cam 171 is passed, then "holding-on" switch 173 is closed.

10 The circuit which includes detector switch 174 and "advance" switch 164 is thus shorted through "holding-on" switch 173. Current then flows from the source 205 through wires 224, 254 to switch 173, thence through the closed contact 255 15 through wires 256, 257 to relay 245, where it passes through contact 251 to wire 261. This wire is connected to wire 231 which was previously shown to lead to other wires and relay 233, then back to generator 205. It follows that the closing of 20 holding-on switch 173 closes an energizing circuit which includes relays 233, 245, and that this circuit remains closed while cam 171 makes substantially half a revolution, a half-revolution representing the passage of one prong 41 over 25 shaft 53.

Contact 252 is also closed by relay 245 and thereby closes an advance motor relay circuit in which energy flows from the A. C. generator 206 through wires 211, 263, 264 to the contact 252 and 30 thence through the relay 245 and wire 265 to a motor advance relay 267 which is energized, the circuit being completed by wires 268, 213 back to the generator 206.

The relay 267 is an element of a reversing 35 switch system the elements of which are located in a box designated by dot and dash lines and indicated generally by the numeral 271. Relay 267, being energized closes contacts 272, 273, 274 of the reversing switch, thereby establishing a 40 circuit in which energy passes from the A. C. generator 206 through wires 211, 212, 213, then through the connected wires 275, 276, 277, the contacts 272, 273, 274, wires 281, 282, 283, and motor wires 284, 285, 286 to motor 191 which 45 rotates in an "advance" direction for at least the passage of one prong 41 over shaft 53. It will continue to operate in the same direction, however, until the lag in prongs 41 is taken up because the energizing of the relays continues 50 as described until a normal condition exists and the circuits opened.

When, due to physical and mechanical maladjustment, the oven prongs 41 are ahead of the 55 delivery lugs 36, the rotation of the synchronizing motor 191 is reversed from the "advance" direction previously mentioned, causing a small degree of retardation in the rotation of the long drive shaft 143, and consequently retarding the prongs 41 relative to lugs 36 to restore them to 60 timed relation with each other.

The reversal of motor 191 is effected in the following manner: With the prongs 41 ahead of the lugs 36, the cams 162, 163 would not have reached the normal position shown in the diagram. It will be necessary to imagine cams 162, 163 rotated counter-clockwise until cam 163 permits switch 165 to close. At such time cam 162, which is integral with cam 163, would also be retarded with respect to cams 171, 172 to the 65 same extent as cam 163, but upon examination of the diagram it is evident that the small counter-clockwise movement would not alter the setting of switch 164, it remaining open at that instant. The closed "reverse" switch 165, how- 70 75

ever, establishes a "reverse" detector circuit in which energy from the D. C. generator 205 passes through wires 224, 225 to switch 174, thence through the switch contact 226 and wires 227, 5 287 to switch 165. The contact 291 now being closed, the current continues through wires 293, 294, 295 to double contact relay 299, which is energized by the current, the circuit being completed by wires 301, 247 and 236 back to generator 10 205.

The energized relay 299 closes contacts 303, 304. A holding-on circuit is then established by contact 304 an instant after this preliminary energization of the relay. The holding-on circuit 15 is similar to that previously described for the advance circuit. The holding-on circuit originates at the D. C. generator 205, current passing through wires 224, 254, contact 255 of switch 173, wires 256, 311, relay contact 303, 20 wires 312, 294 and 295 to relay 299 which is kept energized, the holding-on circuit being completed through wires 301, 247, 236 back to generator 205. Single contact relay 240 is simultaneously 25 energized by the parallel circuit starting at wire 294, thence through wire 313, relay 240, and wires 314, 235, 236.

The functions of single contact relays 233, 240 will here be explained. It should be noted here that there is a possibility of both switches 30 164, 165 being closed at the same time. Relays 233, 240 are so connected into the circuit that it would be impossible at such a time for both relays 245, 299 to be energized at the same time. This obviates the possible danger of trying to 35 energize the synchronizing motor 191 in both "advance" and "reverse" directions at the same time.

The relays 233, 240 cooperate to permit the operation of motor 191 in only the "reverse" direction when such an emergency arises. This function is effected in the following manner. It was shown that either relay 233 or 240 is energized when its respective "advance" or "reverse" switch 164, or 165 is closed. If both switches 45 chance to be closed at the same time, both relays 233, 240 will be energized, then both relay contacts 237, 239 will be open. It was previously shown that current which energized double contact "advance" relay 245 had to pass through 50 the then closed contact 239 of single contact reverse relay 240. But as this contact is open in the emergency condition now being considered, "advance" relay 245 will not be energized. On the other hand, double-contact "reverse" relay 55 299 is energized independently of single contact relays it having been previously explained that this relay is energized in parallel with single contact relay 240. It is therefore obvious that, under the emergency condition being considered, only 60 the "reverse" relay 299 will be energized.

With relay 299 energized, contacts 303, 304 are closed. It was shown that contact 303 closed a holding-on circuit. This circuit will remain closed for a minimum of a half revolution of cam 65 171 when it will be broken by the opening of switch 173.

The other contact 304 of relay 299 closes a circuit which originates at the A. C. generator 206, electrical energy emanating from it through 70 wire 211 and progressing through wires 263, 321, contact 304, relay 299, and wire 322 to reversing switch relay 323 which is thus energized, the circuit being closed through wires 324, 213 to generator 206.

75 The energized relay 323 closes reversing con-

tacts 325, 326, 327 and power is then transmitted from the A. C. generator 206 through the wires 211, 212, 213 and wires 331, 332, 333, contacts 325, 326, 327, thence through wires 334, 335, 336 and motor wires 284, 285, 286 to motor 191, which is thereby energized to rotate in a "reverse" direction causing a retardation, through means already described, of prongs 41 with respect to lugs 36 and the consequent automatic relative readjustment of the timed relation of these parts. 10

It is thought that the invention and many of its attendant advantages will be understood from the foregoing description, and it will be apparent that various changes may be made in 15 the form, construction and arrangement of the parts without departing from the spirit and scope of the invention or sacrificing all of its material advantages, the form hereinbefore described being merely a preferred embodiment 20 thereof.

I claim:

1. A synchronizing mechanism for tandem machines operating upon articles of manufacture, comprising in combination: means for advancing 25 articles in one of said machines, means for advancing articles in another of said machines, a common driving means for said advancing means comprising a prime mover and gearing connected to both of said machines, electro-mechanical detectors associated with both of said advancing means and at the receiving point of said other machine to detect disturbance of timed relation between said advancing means, synchronized means for restoring said timed relation, and 30 means operatively connected to said gearing for driving one of said advancing means while said 35 prime mover is at rest.

2. A synchronizing mechanism for tandem machines operating upon articles of manufacture, 40 comprising in combination, means for advancing articles in one of said machines, means for advancing articles in another of said machines, synchronizing means connecting said advancing means, electro-mechanical detectors associated 45 with both of said advancing means and at the receiving part of said other machine for detecting disturbance of timed relation between said advancing means, said detectors operating in synchronism with their respective advancing means and with each other under normal conditions and adapted to actuate said synchronizing means to automatically restore said advancing means to timed relation with each other when said relation is disturbed, common driving means 50 for said advancing means comprising a prime mover and gearing connected to both of said machines, and means operatively connected to said gearing for driving one of said advancing means while said prime mover is at rest. 55

3. In a synchronizing mechanism for tandem machines operating upon articles of manufacture, the combination of a delivery mechanism in one of said machines, a receiving mechanism in another of said machines, said mechanisms being normally moved in timed relation and having a common driving means comprising a prime mover and gearing connected to both of said mechanisms, electro-mechanical means for maintaining said normal relationship, and means operatively connected to said gearing for driving said receiving mechanism while said prime mover is at rest. 60

4. In a synchronizing mechanism for machines operating in succession on metal sheets, the com- 75

bination of a delivery mechanism in one machine, a receiving mechanism in another machine, said delivery mechanism being normally in timed relation with said receiving mechanism to effect transfer of said sheets from said delivery mechanism to said receiving mechanism, a detecting device associated with said delivery mechanism, a detecting device associated with said receiving mechanism, said detecting devices cooperating to detect maladjustments in the timed relations between said delivery and receiving mechanisms, a synchronizing mechanism comprising a reversible electric motor associated with and controlled by said detecting devices, said synchronizing mechanism being in turn associated with said delivery and receiving mechanism to establish synchronism therebetween and set in motion to effect said synchronism by said detecting devices when a said maladjustment is detected by said devices, common driving means for said delivery and receiving mechanisms comprising a prime mover and gearing connected to both of said mechanisms, and means connected to said gearing for driving said receiving mechanism while said prime mover and said delivery mechanism are at rest.

5. In a synchronizing mechanism for machines operating in succession on metal sheets, the combination of a delivery mechanism in one machine, a receiving mechanism in another machine, feed lugs in said delivery mechanism, receiving prongs in said receiving mechanism, said delivery lugs being normally in timed relation with said receiving prongs to effect transfer of said sheets from said delivery mechanism to said receiving mechanism, detecting cams and switches associated with said delivery lugs, detecting cams and switches associated with said receiving prongs, said detecting cams and switches cooperating to detect maladjustments in timed relation between said delivery lugs and receiving prongs, a synchronizing mechanism associated with and controlled by said detecting cams and switches, said synchronizing mechanism being in turn associated with said delivery lugs and receiving prongs to establish synchronism therebetween, a synchronizing motor included in and driving said synchronizing mechanism, said motor being energized through said detecting switches when a maladjustment is detected, common driving means for said delivery and receiving mechanisms comprising a prime mover and gearing connected to both of said mechanisms, and means connected to said gearing for driving said receiving mechanism while said prime mover and said delivery mechanism are at rest.

6. In a pair of machines operating in tandem upon articles of manufacture, the combination of delivery units associated with the first machine, receiving units associated with the second machine, said delivery and receiving units operating normally in synchronism with each other to facilitate the transfer of said articles from said delivery units to said receiving units, a common driving means for all of said units comprising a prime mover and gearing connected to all of said units, automatic detecting and synchronizing mechanisms associated with said units and cooperating with said common driving means, while said machines are in motion, for detecting maladjustments which disturb normal synchronism between said units and for restoring synchronism to said units when said maladjustments occur, and means operatively connected to said gearing for driving said receiving units while

said prime mover and said delivery units are at rest.

7. In a pair of machines operating in succession upon articles of manufacture, a common driving means for both machines comprising a prime mover and gearing connected to both of said machines, article conveying means in both machines, electro-mechanical synchronism detector and control units associated with moving parts in both machines, a reversible motor mechanically connected with said gearing to increase or decrease the speed of the second machine relative to the first during the operation of said machines, said detector and control units automatically cooperating only when the machines are out of synchronism to start said motor to increase or decrease the speed of said second machine relative to the first until synchronism of operation is restored, and means operatively connected to said gearing for driving one of said article conveying means while said prime mover is at rest.

8. In a pair of machines operating in succession on articles of manufacture, the combination of a common driving means for both machines comprising a prime mover and gearing connected to both of said machines, article conveying means in both machines, electro-mechanical synchronism detector and control units associated with said conveying means in both machines, a reversible motor geared with said gearing to change the speed of the second machine relative to the first during the operation of said machines, said detector and control units automatically cooperating only when the machines are out of synchronism to start said motor and maintain it in operation in either of its reversible directions while synchronism is disturbed, and to stop said motor when synchronism has been restored, and means operatively connected to said gearing for driving one of said article conveying means while said prime mover is at rest.

9. The combination of an oven, a conveyor therein which is subjected to changes in dimensions by the heat of said oven, a feeding conveyor without the oven and operating to deliver parts to the oven conveyor, a motor for driving said feeding conveyor and the oven conveyor shaft at the delivery end of said oven, an auxiliary motor for driving said shaft, means operatively connected to both of said motors for driving said shaft by the second of said motors while the first of said motors is at rest, and automatic means for accelerating and retarding the speed of said shaft at the delivery end of the oven conveyor to synchronize the receiving end of the latter with said feeding conveyor.

10. The combination of an oven, a conveyor therein which is subjected to changes in dimensions by the heat of said oven, a feeding conveyor without the oven and operating to deliver parts to the oven conveyor, a motor for driving said feeding conveyor and the oven conveyor shaft at the delivery end of said oven, an auxiliary motor for driving said shaft, means operatively connected to both of said motors for driving said shaft by the second of said motors while the first of said motors is at rest, and a reversible motor and automatic means for accelerating and retarding the speed of said shaft at the delivery end of the oven conveyor to synchronize the receiving end of the latter with said feeding conveyor.

11. The combination of an oven, a conveyor therein which is subjected to changes in dimen-

sions by the heat of said oven and having prongs thereon, a feeding conveyor without the oven and having lugs thereon operating to deliver parts to said oven conveyor, a motor for driving said feeding conveyor and the oven conveyor shaft at the delivery end of said oven, an auxiliary motor for driving said shaft, means operatively connected to both of said motors for driving said shaft by the second of said motors, while

the first of said motors is at rest, and automatic means for accelerating and retarding the speed of said shaft at the delivery end of the oven conveyor to synchronize the receiving end of the latter with said feeding conveyor and to synchronize the respective operations of said prongs and lugs. 5

WILLIAM PECHY.
